UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

DESIGN FOR A SHADE-BOWL.

50,180.

Specification for Design.

Patented Jan. 16, 1917.

Application filed November 14, 1916. Serial No. 131,340. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Shade-Bowl, of which the following is a specification.

In the accompanying drawing I have illustrated a shade bowl constructed in accordance with my invention.

The device consists of an upright bowl 1 having an ornamental knob 2 at the end of the vertical axis and divided by suitable ridges or lines 3 into sectors 4 each of which bears an ornamental design 5.

Having thus described and illustrated my invention, I claim:

The ornamental design for a shade bowl substantially as shown and described.

Signed by me at Steubenville, Jefferson county, Ohio, this 10th day of November, 1916.

JOHN BEISWANGER.
